POLE KEY ANCHOR

James K. Harper, Centralia, Mo., assignor to A. B. Chance Company, Centralia, Mo., a corporation of Missouri

Application April 11, 1951, Serial No. 220,419

1 Claim. (Cl. 189—92)

1

The present invention relates to expanding pole key anchors, and is particularly concerned with the provision of an improved expanding pole key of the type covered by the prior patent to Edward M. Fee and Charles R. Murrie, No. 2,279,918, issued April 14, 1942.

One of the objects of the invention is the provision of an improved expanding pole key anchor which presents a greater resistance to the movement of the line pole than the devices of the prior art, while utilizing no more steel than such devices of the prior art.

Another object is the provision of an improved expanding pole key in which there are a minimum number of parts, and in which the area of the anchor is increased by utilizing two sets of blades, each set including a pair, and the two pairs acting upon each other to effect expansion.

Another object of the invention is the provision of an improved pole key anchor which is simple in construction, which provides a maximum expanded area and a minimum contracted overall width, and which may be manufactured at a low cost, while providing a greater resistance to movement of the line pole than the devices of the prior art.

Other objects and advantages of the invention will be apparent from the following description and the accompanying drawings, in which similar characters of reference indicate similar parts throughout the several views.

Referring to the two sheets of drawings accompanying the specification,

Fig. 1 is a side elevational view of an expanding pole key anchor embodying my invention, shown in the expanded position;

Fig. 2 is a top plan view, taken on the plane of the line 2—2 of Fig. 1, looking in the direction of the arrows;

Fig. 3 is a fragmentary sectional view, taken on the plane of the line 3—3 of Fig. 1, looking in the direction of the arrows;

Fig. 4 is a front elevational view of the pole key anchor, showing its parts in the contracted position;

Fig. 5 is a side or edge elevational view of the pole key anchor of Fig. 4 in the contracted position;

Fig. 6 is a fragmentary sectional view through the terrain, showing the line pole and pole key anchor in the course of its installation;

Fig. 7 is a sectional view, taken on the plane of the line 7—7 of Fig. 4, looking in the direction of the arrows.

2

Referring to Figs. 1 to 3, 10 indicates in its entirety the pole key anchor embodying the invention, which is provided with four substantially identical blades, which have been numbered 11, 12, 13, and 14 in the order in which they are assembled from front to back in Fig. 1.

These blades may be substantially identical in construction; and each blade may consist of an elongated, substantially rectangular body having the straight side edges 15, 16, rounded end edge 17, and a semi-circular inner edge 18. Each of the blades is formed with a bearing bore 20 on an axis which is the radius of the circular end 18; and the bearing bore is preferably provided with a tubular protuberance 21 used to space one blade from another.

The two blades 11 and 14 are mounted for pivotal movement relative to each other upon a rivet 22. The two blades 12 and 13 are pivotally mounted relative to each other upon a rivet 23. In addition to supporting the blades for pivotal movement, these rivets also include an angular guide 24 and a U shaped guide 25.

The angular guide 24 has a flange 26 extending parallel to the blades and secured by the same rivet, which also passes through the yoke of the U-shaped guide member 25. The U-shaped guide member is substantially rectangular in shape, having a flat yoke and a pair of right angle flanges 27, 28 parallel to each other and spaced sufficiently to slide on the guy rod 29.

The angular guide 24 has the flange 26 mounted on rivet 23 and another flange 30 at right angles to the flange 26, and provided with an aperture 31 for slidably receiving the guy rod 29.

At the lower end of the assembly the rivet 22 also supports an angle member 32 with a pivot flange 33, having an aperture receiving the rivet 22. The pivot flange 33 supports a tamping base 35, as seen in Fig. 3; and the flange 34 and base 35 have the aligned threaded aperture 36 into which the threaded end 37 of the guy rod 29 is threaded.

The rivet 22 also supports a U shaped guide 38, which has the same parallel flanges 27 and 28 for guiding movement on the guy rod 29. Besides being pivoted to each other on the rivets 22 and 23, the plates 11—14 are arranged in pairs and are pivoted together as follows. Plates 12 and 14 are pivoted together on the rivet 39. Plates 11 and 13 are pivoted together 55 by the rivet 40.

In the present invention the spreader struts used in the devices of the prior art have been eliminated and another pair of blades have been substituted therefor. This gives the anchor considerably more area for engagement with the earth to prevent the bottom of the line pole from moving.

The rivets 39 and 40 are located toward one side of each of the anchor blades for the purpose of permitting the blades to expand further and to contract into a more compact shape. Thus when the pole key anchor is contracted, as shown in Figs. 4 and 5, this contracting action can go far enough so that blade 11 hits the rivet head 39 carried by the blade 12.

Another way of determining how far the anchor will collapse is to note that the folding movement can continue until the blade 12 hits the rivet shank of rivet 40.

The mode of use of the anchor is as follows. The guy rod 23 is screwed into the flange 34 and base 35; and the guy rod extends upward between the sides of the guides 28 and 25 and through the hole 34 of guide 24. This definitely determines the position of the rivets 22 and 23 with respect to the guy rod, these rivets having their axes in the same plane which passes through the axis of the guy rod.

The anchor having been collapsed to the position of Fig. 4, the hole about the line pole 41 is made big enough to accommodate the pole key anchor toward one side; and the anchor is placed in the hole against the pole, in the position of Fig. 4.

A tampon bar is then used on the flange 30 of the upper guide 24; and this causes the blades to move downward and outward. As the rivets 22 and 23 approach, the blades are projected outward into the undisturbed earth surrounding the hole until they are fully expanded, as shown in Fig. 1.

The pole key gives the pole an additional bearing surface against the undisturbed earth at the bottom of the pole; and the pole may be provided with a suitable beam 42 engaging the earth near the top of the ground.

All of the parts of the present anchor are preferably constructed out of relatively thin sheet metal, such as steel, excepting, of course, the rivets, which may also be of steel.

Since the blades are substantially rectangular, the only waste encountered is that in drilling the

holes and making one end circular. Due to the stacking of the blades, thinner steel stock can be used than in the anchors of the prior art having only two blades.

While I have illustrated a preferred embodiment of my invention, many modifications may be made without departing from the spirit of the invention, and I do not wish to be limited to the precise details of construction set forth, but desire to avail myself of all changes within the scope of the appended claim.

Having thus described my invention, what I claim as new and desire to secure by Letters Patent of the United States, is:

15 A pole key anchor comprising a plate assembly having a pair of upper anchor blades and a pair of adjacent lower anchor blades, said blades being of similar substantially rectangular elongated plane sheet material, a base plate having a bottom flange and a vertical flange, an upper guide member having a vertical flange and an apertured horizontal flange, said upper blades being pivoted together adjacent their inner ends about a common pivot supported on said vertical flange of 20 said guide member, said lower blades being pivoted together adjacent their inner ends about a common pivot supported on said vertical flange of said base plate, each of said upper blades being pivoted to one of said lower blades intermediate 25 their ends thus providing working portions of said blades extending beyond said last mentioned pivotal connections, a rod for placing the plate assembly into a hole, said rod having a removable connection with said base plate and extending 30 through said apertured flange and a U-shaped yoke on said guide member embracing said rod, said rod maintaining said base plate and guide member in vertical alignment when said blade assembly is actuated to move said blades about 35 their inner pivotal connections to expand the working portions of the same into earth formation.

JAMES K. HARPER.
